(57) **CLAIM**

The ornamental design for the cooking apparatus for hotdogs, as shown and described.

DESCRIPTION

FIG. 1 is a top plan view of a cooking apparatus for hotdogs showing my new design;

FIG. 2 is a bottom plan view thereof;

FIG. 3 is a left side elevational view thereof;

FIG. 4 is a right side elevational view thereof;

FIG. 5 is a front side elevational view thereof;

FIG. 6 is a rear side elevational view thereof; and,

FIG. 7 is a perspective view of the cooking apparatus for hotdogs in condition of use cooking at least one hotdog.

The broken lines are for environmental purposes only and form no part of the claimed design.
